(57) **CLAIM**

The ornamental design for a sensor controller, as shown and described.

DESCRIPTION

FIG. 1 is a front perspective view of our new design for a sensor controller;

FIG. 2 is a front view of the sensor controller of FIG. 1;

FIG. 3 is a top view of the sensor controller of FIG. 1;

FIG. 4 is a bottom view of the sensor controller of FIG. 1; FIG. 5 is a right side view of the sensor controller of FIG. 1;

FIG. 6 is a front elevational view of the sensor controller of FIG. 1 showing the front cover and the side cover opened; and,

FIG. 7 is a front perspective view of the sensor controller of FIG. 1 showing the front cover and the side cover opened. The broken lines shown in connection with the sensor controller are for illustrative purposes only and form no part of the claimed design.
